(57) **CLAIM**

The ornamental design for a thermometer with flavored tip, as shown and described.

DESCRIPTION

FIG. 1 is a top plan view of a thermometer with flavored tip showing my new design;

FIG. 2 is a bottom plan view thereof;

FIG. 3 is a side elevational view thereof;

FIG. 4 is a rear elevational view thereof; and,

FIG. 5 is a front elevational view thereof.

The indicia shown on the figures are for illustrative purposes only and are hereby disclaimed as forming no part of Applicant's claimed invention.

1 Claim, 2 Drawing Sheets

FIG. 1

FIG. 2

FIG. 3

FIG. 4

FIG. 5
